PRESS OPERATING VALVE WITH RAPID ADVANCE AND FULL PRESSURE POSITIONS

Robert K. Sedgwick, Oak Park, Ill., assignor to American Steel Foundries, Chicago, Ill., a corporation of New Jersey

Application March 18, 1948, Serial No. 15,534

7 Claims. (Cl. 121—46.5)

1

This invention relates to hydraulic circuits and more particularly to a novel actuating circuit for an hydraulic motor such as is commonly utilized in a press.

A general object of the invention is to provide an unusually economical circuit having novel means for controlling the rapid advance stroke, the full pressure stroke and the pullback stroke of the hydraulic motor.

In an hydraulic circuit, such as above described, it is frequently desirable to incorporate what is known in the art as a speed change control to slow the advance stroke of the hydraulic motor before the resistance of the work is encountered and to thereafter initiate the full pressure stroke of the motor against the work. In prior art arrangements, many control mechanisms have been introduced for this purpose and usually involve multiplicity of valves and complicated piping arrangements.

Accordingly, it is a primary object of the present invention to devise a single operating valve capable of controlling the rapid advance and pullback strokes of the motor and also capable of effecting speed change control for the purpose above described.

A further object of the invention is to devise a valve, such as above described, incorporating novel means for throttling the discharge of hydraulic fluid from the prefill valve of the hydraulic motor as the pullback phase of the motor's cycle is initiated. By this means, sudden opening of the prefill valve means and consequent noise and damage to the equipment is prevented.

The foregoing and other objects and advantages of the invention will become apparent from a consideration of the following specification and the accompanying drawing, wherein:

Figure 1 is a diagrammatic view of an hydraulic press incorporating the novel circuit, portions of the structure being broken away in vertical cross section to clarify the illustration;

Figure 2 is an enlarged vertical cross sectional view taken on the longitudinal axis of the operating valve with the stem thereof shown in elevation; and

Figure 3 is a cross sectional view taken on the line 3—3 of Figure 2.

Describing the invention in detail and referring first to Figure 1, the press comprises a cylinder casting 2 and a ram 4 having a head 6 defining a main advance chamber 8 and a return or pullback chamber 10 within the casting. The ram 4 is hollow and comprises an internal rapid advance

2

chamber 12 receiving a pipe or tube 14 carried by the casting 2 and slidably fitted in the ram at 16 in substantially fluid-tight engagement therewith. Supported by the casting is a tank or reservoir 18 adapted to contain low pressure fluid communicating with the chamber 8 on the rapid advance stroke and the pullback stroke of the ram and cut off from communication with the main advance chamber 8 on the full pressure stroke of the ram by a prefill valve 20 including a casing 22 with ports 23 connected to the reservoir. The casing contains a stem 24 spring-pressed to its open position by a spring 28 reacting against the casing 22 and a spring seat 30 connected to the stem.

The cycle of the press is controlled by a single operating valve, generally designated 32, and shown in detail in Figures 2 and 3, wherein it will be seen that the valve comprises a body or casing 34 having a longitudinal bore or passage 36 containing a hollow stem 38 having four spools or lands 40, 42, 44 and 46 and also having a longitudinal passage 48 connected to the bore 36 by ports 50, 52, 54 and 56 through the respective lands of the stem.

The body 34 comprises an annular prefill chamber 58, a prefill exhaust or throttle chamber 60, a pair of main exhaust chambers 62 and 64, a rapid advance chamber 66, an inlet or high pressure delivery chamber 68 and a pullback chamber 70.

The prefill exhaust chamber 60 is connected directly to the tank by a port 72, as best seen in Figure 3, and the exhaust chambers 62 and 64 are similarly connected to the tank by ports (not shown). The ends of the bore 36 are connected to the tanks by ports 73.

The inlet chamber 68 is connected by a port 74 (Figure 2) to a pump 76 (Figure 1) operated by a motor 78, the suction side of the pump being connected by a line 80 to the tank 18.

The prefill chamber 58 is connected by a line 82 to the top of the casing 22 above the stem 24 and is connected through a conventional spring-pressed check valve 84 to the main chamber 8 of the hydraulic motor.

The rapid advance chamber 66 of the valve 32 is connected by a line 88 to the tube 14 and the pullback chamber 70 of the valve is connected by a line 90 to the pullback chamber 10 of the hydraulic motor.

As indicated in Figure 1, the valve 32 is preferably actuated by pneumatic motors 92 and 94; however, the valve may be actuated manually or in any other desired manner. The motor 92 is

shown in detail in Figure 2 and comprises a casting 93 receiving a piston 95 connected to a stem or rod 97 adapted to actuate the valve stem 38, as hereinafter described. For the sake of simplicity, the motor 94 is eliminated in Figure 2.

In operation of the novel circuit, the stem 38 is maintained in neutral position as, for example, by the motor 94; and in this position, as best seen in Figure 2, the pressure fluid from the pump 76 is delivered to the inlet chamber 68 and flows through the port 54 and the passage 48 into the ports 52 and 56 and thence to exhaust through the chambers 62 and 64. Under these conditions, the prefill valve casing 22 is exhausted through the line 82, the prefill valve chamber 58 and the prefill exhaust valve chamber 60 inasmuch as the spool or land 40 of the stem 38, as best seen in Figure 2, accommodates flow of fluid from the chamber 58 to the chamber 60.

The stem 38 is actuated to rapid advance position, indicated at the right extremity of Figure 2, by the motor 92 and, in this position of the stem, fluid is delivered from the inlet chamber 68 to the rapid advance chamber 66 and the pullback chamber 70 is exhausted through the exhaust chamber 64. Under these conditions the prefill valve chamber 58 is closed by the prefill land or spool 40.

In the full pressure stroke of the stem 38, indicated at the right of Figure 2, fluid from the inlet chamber 68 is delivered to the rapid advance chamber 66 and thence into the ports 52 which, under these conditions, overlap the chamber 66. The fluid flowing into the ports 52 is conveyed through the passage 48 and the ports 50 into the prefill valve chamber 58 inasmuch as the ports 50, under these conditions, are disposed within the latter chamber. Thus fluid is conveyed to the line 82 (Figure 1) into the casing 22 acting upon the top area of the prefill valve stem 24 to urge the latter to its closed position. The fluid then flows through the check valve 84 which is adapted to create a slight back pressure to close the stem 24 before delivery of fluid through the line 82 to the main advance chamber 8. Under these conditions, pressure is developed against the full cross sectional area of the head 6 on the full pressure stroke of the ram 4. It may be noted in this connection that closing of the prefill valve stem 24 checks the rapid advance stroke of the ram 4 prior to initiation of the full pressure stroke thereof against the work.

In the pullback or reverse position of the stem 38, as indicated at the right of Figure 2, pressure fluid is delivered from the inlet chamber 68 to the pullback chamber 70 and is exhausted from the rapid advance chamber 66 to the exhaust chamber 62. At the same time, the prefill valve chamber 58 is exhausted at a predetermined rate through the port 72. This rate is determined by a throttle screw 96 threaded into the body 34 and held in adjusted position in the port 72 by a lock nut 98. The outer end of the screw is provided with a cap nut 100 protecting a square extremity 102 of the screw adapted for actuation by a suitable tool, such as a wrench.

Thus due to the throttling of fluid exhausted through the port 72, the prefill valve gradually opens at an adjustable predetermined rate preventing shock to the tank as the ram is actuated on the return or pullback stroke thereof by delivery of pressure fluid from the valve pullback chamber 70 through the line 90 to the pullback chamber 10 of the hydraulic motor. At the end

of the pullback stroke, the stem is actuated by the motor 94 to the neutral position shown in Figure 2 preparatory to initiation of a new cycle.

It will be understood that the valve 32 may be actuated by manually operated means or may be automatically actuated by any suitable position or pressure responsive means, such as are well known in the art.

It will be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In an hydraulic actuating circuit for an hydraulic motor having main advance and pullback chambers, ram means presenting main advance and pullback areas in respective chambers and presenting a rapid advance area spaced from the first-mentioned areas, a reservoir of low pressure hydraulic fluid, and prefill valve means adapted in the open position thereof to connect said reservoir and said main advance chamber and adapted in the closed position to cut off communication between said reservoir and said main advance chamber, said prefill valve means comprising a closing pressure area adapted when acted upon by pressure fluid to close said prefill valve means; the combination of an operating valve including a body with an internal bore having a prefill chamber, a prefill exhaust chamber, a main exhaust chamber, a rapid advance chamber, a pressure inlet chamber, a pullback chamber, and another main exhaust chamber spaced in the foregoing sequence along said bore, said exhaust chambers being connected to said reservoir, said prefill chamber being connected to a port of said prefill valve means containing the closing area thereof and also being connected to said main advance chamber through one-way check valve means for accommodating flow of fluid to the main advance chamber after a predetermined back pressure has been built up against said prefill valve area, a connection between the rapid advance chamber and the rapid advance area, and a connection between said pullback chambers, a stem comprising a plurality of lands slidably fitted in said bore, said stem being so formed and arranged that in the neutral position thereof one of said lands accommodates flow of fluid from the prefill chamber to the prefill exhaust chamber, the other exhaust chambers and the inlet chamber being covered by the other lands respectively, passage means through said stem extending through all of said lands and adapted in the neutral position of the stem to connect the inlet chamber to the main exhaust chambers, said stem being adapted in the rapid advance position thereof to close the prefill chamber, to direct flow of fluid from the inlet chamber to the rapid advance chamber and to exhaust flow of fluid from the pullback chamber to said other main exhaust chamber, said stem being adapted in the full pressure position thereof to direct flow of fluid from the inlet chamber to the rapid advance chamber, to direct fluid from the rapid advance chamber through said passage means to the prefill chamber and to exhaust the pullback chamber to said other main exhaust chamber, and said stem being adapted in the reverse position thereof to direct flow of fluid from the inlet chamber to the pullback chamber, to exhaust the rapid advance

chamber to said one main exhaust chamber and to exhaust the prefill chamber to the prefill exhaust chamber, and a source of high pressure fluid connected to the inlet chamber.

2. A circuit, according to claim 1, wherein said body is provided with means for adjustably throttling flow of fluid from the prefill exhaust chamber to the reservoir.

3. An operating valve for delivering pressure fluid comprising a body with an internal bore having a prefill chamber, a prefill exhaust chamber, a main exhaust chamber, a rapid advance chamber, a pressure inlet chamber, a pullback chamber, and another main exhaust chamber spaced in the foregoing sequence along said bore, a stem comprising a prefill land, an inlet land, and a pair of exhaust lands slidably fitted in said bore, said stem being so formed and arranged that in the neutral position thereof said prefill land accommodates flow of fluid from the prefill chamber to the prefill exhaust chamber, the other exhaust chambers and the inlet chamber being covered by the exhaust lands and the inlet land respectively, passage means through said stem having ports extending through respective lands and otherwise spaced from said bore, said passage means being adapted in the neutral position of said stem to connect the inlet chamber to the main exhaust chambers, said stem being so formed and arranged that in the rapid advance position thereof said prefill land closes said prefill chamber positively preventing flow of fluid therethrough while the inlet land and one exhaust land accommodate flow of fluid from the inlet chamber to the rapid advance chamber and the other exhaust land accommodates flow of fluid from the pullback chamber to the exhaust chamber, said stem being so formed and arranged that in the full pressure position thereof the ports in said one exhaust land overlap the rapid advance chamber and the ports in the prefill land communicate with the prefill chamber, said one exhaust land accommodating flow of fluid from the inlet chamber to the rapid advance chamber and said other exhaust land accommodating flow of fluid from the pullback chamber to said other exhaust chamber, and said stem being so formed and arranged that in the reverse position thereof the inlet land and said other exhaust land accommodate flow of fluid from the inlet chamber to the pullback chamber and said one exhaust land accommodates flow of fluid from the rapid advance chamber to the first-mentioned exhaust chamber and the prefill land accommodates flow of fluid from the prefill chamber to the prefill exhaust chamber.

4. A valve, according to claim 3, wherein said body is provided with means for adjustably throttling flow of fluid from the prefill exhaust chamber.

5. A valve comprising a body with an internal bore having seven chambers, a stem in said bore having four lands slidably fitted within the bore, the stem being so formed and arranged that in the neutral position thereof the first land accommodates flow of fluid between the first and second chambers while the second, third and fourth lands cover the third, fifth and seventh chambers respectively, a passage through said stem having ports connected to each land, the ports in the second, third and fourth lands being disposed within chambers covered thereby in the neutral position of the stem while the ports in the first land are spaced from the first chamber, said stem being so formed and arranged that in a first advance position thereof the third land accommo-

dates flow of fluid between the fourth and fifth chambers and the fourth land accommodates flow of fluid between the sixth and seventh chambers and the second land accommodates flow of fluid between the second and third chambers, the first chamber being blocked by the first land and all ports being blocked by engagement with the bore, said stem being so formed and arranged that in a second advance position thereof the ports in the first land are disposed within the first chamber and the ports in the second land overlap the fourth chamber to accommodate flow of fluid between the fourth and fifth chambers and through the passage to the first chamber, the fourth land accommodating flow of fluid between the sixth and seventh chambers, and said stem being so formed and arranged that in a reverse position thereof the first and second lands accommodate flow of fluid between the first and second chambers, the second and third lands accommodate flow of fluid between the third and fourth chambers and the third and fourth lands accommodate flow of fluid between the fifth and sixth chambers, all of the ports being blocked by engagement with the bore, a port connected to each chamber, and means for adjustably throttling flow of fluid through the port of the second chamber.

6. A valve comprising a body with an internal bore having seven chambers, a stem in said bore having four lands slidably fitted within the bore, the stem being so formed and arranged that in the neutral position thereof the first land accommodates flow of fluid between the first and second chambers while the second, third and fourth lands cover the third, fifth and seventh chambers respectively, a passage through said stem having ports connected to each land, the ports in the second, third and fourth lands being disposed within chambers covered thereby in the neutral position of the stem while the ports in the first land are spaced from the first chamber, said stem being so formed and arranged that in a first advance position thereof the third land accommodates flow of fluid between the fourth and fifth chambers and the fourth land accommodates flow of fluid between the sixth and seventh chambers, the first chamber being blocked by the first land and all ports being blocked by engagement with the bore, said stem being so formed and arranged that in a second advance position thereof the ports in the first land are disposed within the first chamber and the ports in the second land overlap the fourth chamber to accommodate flow of fluid between the fourth and fifth chambers and through the passage to the first chamber, the fourth land accommodating flow of fluid between the sixth and seventh chambers, and said stem being so formed and arranged that in the reverse position thereof the first and second lands accommodate flow of fluid between the first and second chambers, the second and third lands accommodate flow of fluid between the third and fourth chambers and the third and fourth lands accommodate flow of fluid between the fifth and sixth chambers, all of the ports being blocked by engagement with the bore.

7. In an hydraulic actuating circuit for an hydraulic motor having main advance and pullback chambers, ram means presenting main advance and pullback areas in respective chambers and presenting a rapid advance area spaced from the first-mentioned areas, a reservoir of low pressure hydraulic fluid, and prefill valve means

adapted in the open position thereof to connect said reservoir and said main advance chamber and adapted in the closed position to cut off communication between said reservoir and said main advance chamber, said prefill valve means comprising a closing pressure area adapted when acted upon by pressure fluid to close said prefill valve means; the combination of an operating valve including a body with an internal bore having a prefill chamber, a prefill exhaust chamber, a main exhaust chamber, a rapid advance chamber, a pressure inlet chamber, a pullback chamber, and another main exhaust chamber spaced in the foregoing sequence along said bore, said exhaust chambers being connected to said reservoir, said prefill chamber being connected to a port of said prefill valve means containing the closing area thereof and also being connected to said main advance chamber through one-way check valve means for accommodating flow of fluid to the main advance chamber after a predetermined back pressure has been built up against said prefill valve area, a connection between the rapid advance chamber and the rapid advance area, and a connection between said pullback chambers, a stem comprising a plurality of lands slidably fitted in said bore, said stem being so formed and arranged that in the neutral position thereof one of said lands accommodates flow of fluid from the prefill chamber to the prefill exhaust chamber, the other exhaust chambers and the inlet chamber being covered by the other lands respectively, passage means through said stem extending through all of said lands and adapted in the neutral position of the stem to
